UNITED STATES PATENT OFFICE.

LLOYD V. LEWIS, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed October 6, 1923. Serial No. 666,923.

To all whom it may concern:

Be it known that I, LLOYD V. LEWIS, a citizen of the United States, residing at Edgewood Borough, in the county of Allegheny and State of Pennsylvania, have invented certain new and useful Improvements in Railway-Traffic-Controlling Apparatus, of which the following is a specification.

My invention relates to railway traffic controlling apparatus, and particularly to apparatus of the type comprising train carried governing apparatus controlled by energy received from the trackway.

I will describe one form and arrangement of apparatus embodying my invention, and will then point out the novel features thereof in claims.

In the accompanying drawings, Figs. 1 and 1^a when arranged in the order named from left to right comprise a diagrammatic view showing one form of train carried governing apparatus embodying my invention. Fig. 2 is a view partly diagrammatic, showing one form of receiving apparatus through the medium of which the governing apparatus shown in Fig. 1 may be controlled by energy received from the trackway. Fig. 3 is a diagrammatic view showing one form and arrangement of apparatus for supplying energy to the trackway for the control of the governing apparatus illustrated in Fig. 1. Fig. 4 is a fragmental view, showing the relation of the parts of valve P when the valve is in the service or brake applying position. Fig. 5 is a fragmental view showing to an enlarged scale, a part of valve V.

Similar reference characters refer to similar parts in each of the several views.

Referring first to Fig. 3, the reference characters 2 and 2^a designate the track rails of a railroad over which traffic normally moves in the direction indicated by the arrow. These rails are divided, by means of insulated joints 40, into a plurality of successive track sections B—C, C—D, etc. Each such track section is provided with a track relay designated by the reference character T with an exponent corresponding to the location, and connected across the track rails adjacent the entrance end of the section. Each track section is provided also with a source of track circuit current which as here shown comprises a track transformer designated by the reference character G with

an exponent corresponding to the location 55 and having its secondary winding 10 constantly connected across the rails adjacent the exit end of the section. Interposed between the secondary 10 of each track transformer and one rail 2 of the associated section is an impedance 107 one function of which is to limit the output of the associated transformer when its terminals are short-circuited by the wheels and axles of a train. The primary 11 of each track transformer is constantly supplied with alternating current from the secondary of a line transformer designated by the reference character H with a suitable exponent. The primary of each such line transformer is supplied with 65 alternating current from an alternator O over line wires 23 and 23^a.

Each track section is thus provided with a track circuit comprising a track relay T, the secondary winding 10 of a track transformer G, an impedance 107, and the two rails of the section in series.

Means are also provided for supplying to the rails of each section in parallel a current (which I shall hereafter term a "local" current) from a local transformer designated by the reference character L with an exponent corresponding to the location. Each local transformer L has its primary winding 29 constantly supplied with alternating current from the associated line transformer H. Each section is provided with an impedance 18 connected across the rails adjacent the entrance end of the section, a similar impedance 20 connected across 75 the rails adjacent the exit end of the section, and a third similar impedance 19 connected across the rails at a point in the section more than maximum braking distance from the exit end of the section, that is, 80 impedance 19 is so located that a train passing this point at maximum speed could, by proper brake application, be brought to a stop before reaching the exit end of the section. Referring particularly to section 100 B—C, one local circuit passes from secondary 21 of local transformer L^c, through wire 27^a, front contact 25 of track relay T^c, wire 27, impedance 20 in section B—C, through both rails of the section in parallel 105 to impedance 18, and wire 28 back to secondary 21 of local transformer L^c. This circuit is closed only when relay T^c is en-

22 ergized under which condition local current is supplied to section B—C between impedances 18 and 20. When track relay T^c is de-energized, back contact 25 is closed and local current is supplied to the section B—C between impedances 18 and 19 over a circuit which passes from secondary 21 of transformer L^c, through wire 27^a, back contact 25 of relay T^c, wire 32, impedance 19 10 in section B—C, through both rails of the section in parallel to impedance 18, and wire 28 back to transformer L^c.

15 It will thus be clear that each track section is provided with track circuit current and with local current throughout its length except when the track relay for the section 20 next in advance is de-energized, as by a train occupying the associated section under which condition said former section is provided with track circuit current throughout its length and with local current between impedances 18 and 19.

25 Referring now to Fig. 2 the train carrying receiving apparatus here shown comprises two inverted U-shaped magnetizable cores 22^a mounted in front of the forward axle on the locomotive and arranged transversely above the two track rails 2 and 2^a respectively, each of these cores being provided 30 with a winding designated by the reference character F^T. Located at some other point on the train, such as in rear of the first axle, is another pair of magnetizable cores 22^b, located above the track rails 2 and 2^a, respectively, and disposed transversely with respect thereto, each of these cores carrying a winding F^T. The windings F^T, which I will term "track" windings, are so connected that the voltages induced therein by 35 current flowing in opposite directions in the two rails at any given instant are additive and so it will be seen that track circuit current in the rails will induce current in the circuit including the windings F^T. These 40 two windings I will hereinafter refer to collectively as the "track coil." The two windings F^L are so connected that the voltages induced therein by current flowing in the same direction in the two rails at a given 45 instant are additive and so it will be seen that local current in the track rails will induce current in the circuit including windings F^L. These two windings I will hereinafter refer to collectively as the "local 50 coil." The terminals a and b of the track coil F^T are connected through suitable amplifying means N to winding 35 of a two element relay K. The terminals a' and b' of the local coil F^L are connected through suitable 55 amplifying means N^a to the remaining winding 34 of relay K. This relay K is provided with a contact finger 37. When rails 2 and 2^a are supplied with both track circuit current and local current, both windings 34 and 35 of this relay are energized

and contact 37 is closed. When the supply of either track circuit current or local current is discontinued from that portion of track occupied by the locomotive, the de-energization of the corresponding relay 70 winding causes the relay to become de-energized and open its front contact 37. The relay K controls a circuit including a source of energy, as a battery J and a magnet valve device A which in turn controls the 75 brake application apparatus as shall appear in detail hereinafter. It is therefore clear that when relay K is energized, magnet A is energized, but when relay K is de-energized magnet A is de-energized. 80

Referring now to Figs. 2 and 3 the operation of the apparatus thus far described is as follows: As shown in the drawing the trackway apparatus illustrated in Fig. 3 is in the normal condition, that is, the apparatus is in the condition assumed when uninfluenced by the presence of trains. If a train provided with the apparatus illustrated and described in connection with Fig. 2 enters section B—C at point B, voltages are induced in the track coil and the local coil by track circuit current and local current, respectively, in the rails of the section. These induced voltages, having been amplified by devices N and N^a are effective 95 to cause currents to flow in windings 35 and 34 of relay K which thereupon closes its front contact 37 and energizes magnet valve A. Relay K and hence valve magnet A are maintained in their energized condition as 100 the train passes through the portion of track shown in the drawing.

I will now assume that section C—D is occupied by a train. Relay T^c is therefore de-energized and section B—C is supplied with local current between impedances 18 and 19 but not with local current between impedances 19 and 20. If now a second train equipped with apparatus embodying my invention enters section B—C, magnet 110 valve A thereon will be energized as before until the train passes impedance 19. Between impedances 19 and 20 however, the interruption of the supply of local current to the rails causes winding 34 of relay K 115 to become de-energized and this relay therefore opens contact 37 and de-energizes magnet valve A. As the train enters section C—D, the interruption of track circuit current causes winding 35 of relay K to become 120 de-energized and magnet valve A is therefore maintained in its de-energized condition, even though the local coil becomes energized by local current in section C—D.

Referring now to Figs. 1 and 1^a, the train 125 is provided with fluid pressure braking apparatus including a brake pipe 3 containing a fluid preferably air, under pressure. When the pressure in this brake pipe 3 is reduced, the brakes are applied in the usual and well 130

known manner. The reduction in pressure in the brake pipe 3 may be manually performed by means of the engineer's brake valve P, or may be accomplished automatically by the brake application valve S as will appear hereinafter.

The engineer's brake valve P comprises a valve body 38 provided with a valve chamber 6^a. Rotatably mounted in this chamber is a valve member 39 adapted to engage a valve seat 39^a. The abutting surfaces of valve member 39 and valve seat 39^a are provided with valve ports and certain of these ports may be brought into registration by manipulation of the handle 41. Valve body 38 is also provided with a cylinder 42 containing a piston 43. The piston 43 is provided with a projection 43^a adapted to close port 44 to atmosphere when piston 43 is in its lower position. Fluid pressure from brake pipe 3 is constantly supplied to cylinder 42 on the under side of piston 43. When valve member 39 is in the position corresponding to the running position of valve P, pipe 3 is also connected with the cylinder 42 on the upper side of piston 43 and with a source of fluid pressure through pipe 6, feed valve 47 and port 48. The supply of fluid pressure to pipe 6 will be explained hereinafter. An equalizing reservoir 45 is constantly connected with cylinder 42 on the upper side of piston 43. When valve P is in the running position, therefore, as shown in the drawing, the same fluid pressure exists in brake pipe 3, port 48, equalizing reservoir 45, and on both sides of piston 43 in cylinder 42. The area over which this pressure is effective upon the lower side of piston 43 is less, due to the projection 43^a, than the area upon which the pressure is effective upon the upper face of the piston, and the piston is therefore held in its lower position, thereby closing port 44. If valve P is moved to the service position, pipe 3 is disconnected from port 48, and from the cylinder 42 above piston 43. Simultaneously, equalizing reservoir 45 is connected with a reduction limiting reservoir 46 which is connected with atmosphere through port 50^a when the valve P is in the running position. The fluid pressure in reservoir 45 and hence in cylinder 42 above piston 43 is thereby reduced by an amount which is dependent upon the relative volumes of the two reservoirs 45 and 46. Brake pipe pressure is still supplied to cylinder 42 below piston 43 and this pressure being greater than that now applied to the upper side, the piston 43 is forced upward, opening port 44 and venting brake pipe 3 to atmosphere. The resulting decrease in brake pipe pressure causes the brakes to be applied. When the brake pipe pressure has been reduced to a value slightly less than the pressure existing in reservoirs 45 and

46, piston 43 is moved downwardly, closing port 44 and preventing unnecessary lowering of brake pipe pressure. When valve P is returned to the running position, normal pressure is restored to brake pipe 3 and equalizing reservoir thus releasing the brakes and restoring the apparatus to normal. For purposes which will appear as the description proceeds, fluid pressure is constantly supplied to chamber 6^a and this chamber is connected with pipe 49 when valve P is in the service position. Pipe 5 is vented to atmosphere through port 50 when valve P is in the running position, but closed by member 39 when valve P is moved to the lap position.

The brake application valve S comprises a valve body 51 provided with a cylinder 4^a containing a reciprocable piston 53. The valve body 51 also contains a valve chamber 55 containing a slide valve 56 operated by piston 53. Chamber 55 is constantly supplied with fluid pressure from some convenient source such as a main reservoir this source being indicated by the letters M. R. Chamber 4^a is constantly connected with a pipe 4 which is at times vented to atmosphere. When this pipe is closed, fluid pressure admitted to chamber 4^a through a restricted vent 53^a in the piston 53 from chamber 55 equalizes the pressure on the two sides of piston 53 and allows spring 52 to force piston 53 and slide valve 56 attached thereto into their right hand, or release positions. Valve body 55 is provided with a recess divided into an upper chamber 8^a and a lower chamber 3^a by a piston 54. This piston is provided on its lower face with a recess 54^a adapted to slidably receive the end of a valve 54^b. This valve is maintained in position against the lips of recess 54^a by means of a spring 54^b. When piston 54 is in its normal position, valve 54^b closes vent 57. Pipe 3 is constantly connected with chamber 3^a and an equalizing reservoir 8 is constantly connected with chamber 8^a. When valve S is in the release position, as shown in the drawing, brake pipe 3 is connected also with chamber 8^a and a reduction limiting reservoir 17 is connected to atmosphere by means of port 16. Under these conditions the pressures above and below piston 54 are the same but the effective area of the upper side of this piston is greater than the effective area of the lower side because of valve 54^b, and piston 54 is therefore moved downwardly closing vent 57. If chamber 4^a is opened to atmosphere by venting pipe 4, the unequal pressures on the two sides of piston 53 cause this piston and hence valve 56, to be moved to their left hand, or application positions. This operation disconnects pipe 3 from chamber 8^a and disconnects reservoir 17 from atmosphere. Simultaneously, equalizing reservoir 8 is

connected with reservoir 17, thus reducing the pressure in reservoir 8, and consequently in chamber 8^a, by an amount which is dependent upon the relative volumes of the two reservoirs. Since pipe 3 is still connected with chamber 3^a, the pressure above piston 54 is less than that below, and the piston is therefore moved upwardly, opening vent 57 and thus reducing the pressure in pipe 3 through vent 57 and port 16, and causing the brakes to be applied on the train. When the pressure in pipe 3 is reduced below the pressure existing in chamber 8^a, piston 54 is moved downward closing vent 57 and preventing further reduction in brake pipe pressure. Should the engineer make a further brake application, by manually operating his brake valve to decrease the pressure in pipe 3, the pressure in chamber 3^a of valve S being thus reduced below that of chamber 8^a, piston 54 is forced downwardly against the bias of spring 54^b and thereby uncovers a groove 58 in the wall of chamber 3^a, by means of which the pressures on the two sides of piston 54 are equalized. When the pressure in chamber 8^a has been reduced to that existing in chamber 3^a, piston 54 is again allowed to move upwardly and cover groove 58.

When valve 56 is in the release position fluid pressure is supplied from chamber 55 to pipe 6 and feed valve 47 for charging the brake pipe and releasing the brakes after a brake application. When valve 56 is in the application position, however, pipe 6 is disconnected from chamber 55 and under this condition no manipulation of valve P can operate to re-charge the brake pipe. It follows that subsequent to an automatic application of the brakes by valve 56, the brakes can be released only by first restoring valve S to normal position and then properly manipulating valve P.

To accomplish this, pipe 4 is closed. Pressure supplied to chamber 4^a through port 53^a now builds up to such a value as to allow spring 52 to move valve 56 into the release position. This movement reconnects pipe 6 with chamber 55 and allows the engineer to release the brakes by moving his valve P to the running position. It will be noted however that when valve 56 is in the application position, pipe 5 is connected to pipe 4 by means of port 110 and pipe 59. Pipe 5 is open to atmosphere through valve P except when valve P is in the lap position and it is therefore plain that after having incurred an automatic brake application, pipe 4 being closed it is necessary for the engineer, in order to release the brakes, first to move valve P to the lap position to restore valve S, then to move valve P to the running position to charge brake pipe 3 through pipe 6 which is then supplied with fluid pressure from chamber 55.

I have stated that pipe 4 is at times opened to atmosphere and at times closed. I will now describe the apparatus by which this is accomplished in accordance with the speed of the train and traffic conditions in advance of the train.

I have already explained, in connection with Fig. 2, how magnet valve device A is controlled. This device is shown at the right hand side of Fig. 1 and comprises a magnet double pin valve and is of a type which is in such common use as to require no further explanation, it being necessary only to state that when the winding of the device is energized, pipe 24 is supplied with fluid pressure through the valve A from some suitable source such as the main reservoir as indicated at M. R. and when the winding of the device A is de-energized pipe 24 is disconnected from such source and connected with atmosphere through port 61. Fluid pressure in pipe 24 controls a repeater slide valve T as follows: The valve T comprises a valve body 62 having a cylinder 63 containing a piston 63. The valve body 62 also is provided with a valve chamber 64 containing a slide valve 65 operated by piston 63. Main reservoir pressure is supplied to chamber 64 and to the left hand side of piston 63 as shown at M. R. Pipe 24 is connected with chamber 64, and when magnet valve A is energized main reservoir pressure is supplied to the right hand side of piston 63. Under this condition the fluid pressures on the two sides of piston 63 are equal and spring 26^a moves piston 63 and valve 65 to their left hand positions. When magnet valve A is de-energized, however, chamber 26 is opened to atmosphere. Main reservoir pressure on the left hand side of piston 63 then drives this piston and slide valve 65 operated thereby, into their right hand positions.

An auxiliary slide valve U similar to repeater slide valve T is controlled by this latter valve in such manner that when valve T is in its left hand position main reservoir pressure is supplied from chamber 64, through pipe 31^a to chamber 31. Under this condition, the combined force of this pressure and spring 31^b against piston 66 causes this piston to move to the left hand position against the action of main reservoir pressure supplied to chamber 67. When pipe 31^a is opened to atmosphere, main reservoir pressure in chamber 67 moves piston 66 and valve 68 to their right hand positions.

Associated with repeater slide valve T is a timing valve Z. This valve comprises a cylinder divided into an upper chamber 1 and a lower chamber 9 by a piston 70. Chamber 1 is constantly supplied with pressure from main reservoir M. R. through pipe 77 and port 1. When valve 65 is in its left hand position, pipe 77 is connected with a

blow-down reservoir 15, thus charging this reservoir to main reservoir pressure. Chamber 69 is constantly connected with reservoir 15 by port 75 and pipe 15^a. Under these conditions equal pressures exist on both sides of piston 70 which is thereupon moved upwardly by spring 80. It will be observed that when piston 70 is in its upper position the pressure in chamber 1 is effective upon a portion only of piston 70 and that the remaining portion of this surface of the piston is subjected to the pressure in chamber 69 through a restricted port 81. When slide valve T is in its right hand position reservoir 15 and hence chamber 69 are disconnected from main reservoir pressure and connected with pipe 13. If now the pressure in pipe 13 is reduced, by dissipation to atmosphere through restricted port 78 or by means to be described hereinafter, the pressure in chamber 69 will be gradually decreased. When this pressure has been sufficiently reduced, the force exerted on top of piston 70 by main reservoir pressure in chamber 1 will be sufficient to move piston 70 downwardly against the combined action of spring 80 and the pressure in chamber 69. The time required for this operation to take place depends of course upon the rate at which the pressure in chamber 69 is reduced. In moving downward piston 70 engages plunger 73 which in turn opens valve 71 and vents chamber 31 of valve U to atmosphere through pipe 31^a and ports 76 and 72. Pipe 31^a being disconnected from its source of fluid pressure by the reversal of valve T, this venting results in the reversal of valve U as hereinbefore described.

It is clear, therefore, that following reversal of valve T, a time interval elapses before timing valve Z reverses to operate valve U, and that the extent of this time interval is a function of the rate at which the pressure in reservoir 15 is reduced. Means are provided for regulating this rate in accordance with the speed of the train as follows.

The reference character E designates a speed governor comprising a suitable casting containing a rotatable shaft 83 operatively connected with a wheel of the train. Pivotaly supported by this shaft are two arms 84 each carrying a weight 84^a at its outer extremity. When shaft 83 is rotated during motion of the train weights 84^a are swung outwardly by centrifugal force and thereby cause the inner ends of the arms 84 to move a crosshead 86 toward the left against the bias exerted by a spring 85. It is clear that the position of crosshead 86 will therefore be proportional to the speed of the train.

A blow-down valve X is provided with a stem 87 adapted to be engaged by a screw

86^a in crosshead 86. Pipe 13 is connected, by means of valve V (whose function will appear in detail hereinafter), and pipe 12, with valve X. This valve is so arranged that pipe 12 is vented to atmosphere thereby through an aperture whose size is dependent upon the speed of the train. For example, the proportions of this valve may be such that when the speed of the train is below a low speed such as 15 miles per hour the reduction in pressure in pipe 13 necessary to reverse timing valve Z when valve T is reversed takes place only through ports 87^a and 87^b, and port 78 in pipe 13, and consumes a maximum amount of time such as 40 seconds. As the train speed increases port 87^b is opened so that when the speed of the train exceeds some intermediate speed as 35 miles per hour, the reduction in pressure in reservoir 15 takes place through ports 78, 87^a and 87^b and also through port 87^b and the time interval is a minimum, as 5 seconds, the time interval varying in inverse proportion to the train speed between these limits in accordance with the proportion of port 87^b which is uncovered.

It is therefore clear that following a de-energization of valve A and the consequent reversal of valve T, if the train speed is above 35 miles per hour, valve Z will be reversed at the expiration of 5 seconds, if the train speed is below 15 miles per hour, the valve Z will be reversed at the expiration of 40 seconds, and if the train speed is between 35 and 15 miles per hour, the reversal of valve Z will occur after a period of time between 5 and 40 seconds and dependent upon the train speed.

Operated also by speed governor E is a pin valve Y having a valve stem 88 arranged to be engaged by a screw 86^b in crosshead 86 to move against the bias of spring 88^a to open to atmosphere pipe 9. The ports are so proportioned that valve Y is open at all speeds above some low speed as 15 miles per hour. Pipe 9 is constantly connected with a stop reservoir 14 through a check valve 89, the purpose of which will be explained hereinafter.

When valves U and T are in the normal positions, that is, the left hand position, stop reservoir 14 is connected to atmosphere through pipes 14^a, 14^b and port 79. When valve U is reversed reservoir 14 is disconnected from pipe 14^b and pipe 9 is simultaneously connected with pipe 4. It therefore follows that following a de-energization of magnet A, and the reversal in order of valves T, Z and U, brake application valve S will be reversed by venting chamber 4^a to atmosphere if valve Y is open. The resulting brake application will reduce the train speed below 15 miles per hour, thus closing valve Y.

If now the engineer wishes to release the

brakes, he first moves brake valve P to the lap position as before described, closing pipe 5. Fluid pressure admitted to chamber 4^a through port 53^a thereupon builds up, but this port is of small size and the volume of reservoir 14 is considerable and there is therefore a delay or penalty interval before valve S reverses, the duration of this interval being dependent upon the volume of reservoir 14.

If the engineer is alert he may prevent this penalty by proper manipulation of the engineer's acknowledging valve Q, subsequent to the de-energization of magnet valve A and prior to the reversal of auxiliary slide valve U. Associated with the manually operable engineer's acknowledging valve Q is a stop acknowledging valve W comprising a valve cylinder 94 containing a reciprocable piston 93. Associated also with valve Q is an acknowledging reservoir 33. This reservoir 33 is normally supplied with fluid pressure from main reservoir through port 33^a. When valve Q is reversed by manipulation of handle 91, reservoir 33 is disconnected from main reservoir pressure and connected with chamber 94 of valve W by means of port 92, pipe 7, a port 7^a in the brake application valve S open only when this valve is in the release position and pipe 7^a. For the sake of simplicity, these ports are here shown detached from the valve S by which they are operated. When valve S is in the release position and valve Q is reversed, reservoir 33, previously charged to main reservoir pressure, is connected with chamber 94 of valve W. The upper side of piston 93 is subjected to atmospheric pressure and this piston is therefore moved upward, engaging the stem of valve device 96 and moving this valve against the combined force exerted by spring 97 and main reservoir pressure on the upper surface of the valve, into a position wherein main reservoir pressure is supplied to pipe 90. Piston 93 is provided with a port 93^a which allows pressure in reservoir 33 to be dissipated to atmosphere through port 95, so that after a definite time interval spring 98 again acts to move piston 93 downward, and spring 97 then acts to close valve 96. Valve 96 can thereafter be opened only by returning acknowledging valve Q to normal to re-charge reservoir 33 to main reservoir pressure and thereafter again reversing this valve to perform the operations already described. When valve T is reversed and valve U is normal, that is, during the time interval following de-energization of magnet A and prior to reversal of valve Z, pipe 90 is connected, through pipes 14^a and 14^b, with stop reservoir 14. If, under these conditions, stop acknowledging valve W is operated by proper manipulation of valve Q, stop reser-

voir 14 is charged to main reservoir pressure. The check valve 89 prevents dissipation of this pressure through pipe 9. If valve U is now reversed, valve Y being open, the brake application valve S is reversed to apply the brakes, but stop reservoir 14 being charged to main reservoir pressure, no penalty is imposed after the speed of the train is reduced to 15 miles per hour, but the engineer may immediately restore valve S to the release position by moving the valve P to the lap position.

Associated with valve P is a pilot valve V comprising a valve body 99 provided with a cylinder 100 containing a reciprocable piston 101. Valve body 99 is also provided with a valve chamber 106 constantly connected with pipe 13. This chamber 106 contains a slide valve 102 operated by piston 101. When brake application valve P is in the running position, cylinder 100 is open to atmosphere through pipe 49 and port 50 and spring 104 holds piston 101 in its upper position. Under these conditions chamber 106 is connected with pipe 12 through a large port 105. If valve P is moved to the service position to make a brake application as shown in Fig. 4 pipe 49 is connected with chamber 6^a, and main reservoir pressure is therefore supplied to cylinder 100. The lower side of piston 101 is subjected to atmospheric pressure through port 107 and this piston is therefore forced downward and valve 102 is moved against the bias of spring 104 to close port 105 and to connect chamber 106 with pipe 12 through a restricted port 103 equal in size to port 87^a in valve X as best shown in Fig. 5.

It will be clear from the foregoing that if the train is proceeding at any speed in excess of 15 miles per hour, and if the brakes are being manually applied, valve V operates to impose the maximum delay period of 40 seconds before valve Z reverses following reversal of valve T, irrespective of the amount of opening of valve X, and hence irrespective of the speed of the train.

In explaining the operation of the apparatus as a whole I will assume that section C—D of the stretch of track shown in Fig. 3 is occupied by a train. If now, a second train provided with apparatus embodying my invention as illustrated in Figs. 1, 1^a and 2 enters section B—C magnet valve A will be energized until the train passes impedance 19. I will also assume that the engineer's brake valve is in the running position. Repeater slide valve T, timing valve Z and auxiliary slide valve U are in the normal position, as shown in the drawing, and brake application valve S is therefore in the release position. Under these conditions, the brakes on the train are released whatever the speed of the train.

I will now assume that the train passes impedance 19 in section B—C at a speed in excess of 15 miles per hour and that the engineer does not operate either his acknowledging valve or the brake valve P. Valve Y is therefore open. The de-energization of magnet valve A causes valve T to reverse, thus connecting blow-down reservoir 15 and chamber 69 of timing valve Z with blow-down valve X through port 105 of valve V. After a time interval the length of which depends upon the position of valve X in accordance with the speed of the train, timing valve Z reverses, thereby reversing valve U. This movement of valve 68 vents chamber 4^a of valve S to atmosphere through pipe 4 and valve X. Brake application valve S thereupon reverses, applying the brakes as hereinbefore described. This brake application continues till the engineer takes proper steps to manually release the brakes which operation cannot be performed till the speed of the train is reduced below 15 miles per hour. When the train speed has been reduced to a value below 15 miles per hour valve Y is closed. If now the engineer moves his valve P to the lap position, pipe 5 is disconnected from atmosphere and after the penalty delay period required to charge reservoir 14, brake application valve S is reversed. The engineer can then release the brakes by moving valve P to the running position. If however the train speed again exceeds 15 miles per hour the brakes will be applied immediately by the opening of valve Y, the timing valve Z still being reversed. After the speed has been reduced to 15 miles per hour the brakes may be released as before, it being noticed that no penalty delay is imposed under these conditions, the pressure previously supplied to reservoir 14 having been trapped therein by check valve 89.

If the acknowledging valve Q is operated after the train passes impedance 19 and prior to the reversal of valve U reservoir 14 will be charged to main reservoir pressure through valve W. The operation of the apparatus will be the same as just explained except that no penalty delay will be required to charge reservoir 14.

If the train passes impedance 19 at a speed below 15 miles per hour the maximum delay period of 40 seconds will elapse following the de-energization of magnet valve A before the reversal of timing valve Z. The reversal of valve U will connect chamber 4^a of valve S with reservoir 14. As a result the pressure in chamber 4^a will be so reduced that valve S will be reversed although valve Y is closed. It is clear that if the acknowledging valve Q is operated after the train passes impedance 19 and prior to the reversal of valve U, reservoir 14 will be charged to main reservoir pressure

and the subsequent reversal of valve U will not then reverse valve S.

I will now assume that the train passes impedance 19 at a speed in excess of 15 miles per hour but that the engineer has previously moved valve P to the service position so that the brakes are being applied. Slide valve 102 of pilot valve V is therefore in its lower position and the maximum time interval therefore elapses before timing valve Z reverses irrespective of the train speed. At the expiration of this time interval however valve Z and valve U reverse and cause a further brake application by reversing brake application valve S. The brakes can subsequently be released only by bringing the train speed below 15 miles per hour, moving the valve P to the lap position and, after the expiration of the penalty delay period, moving valve P to the running position to charge brake pipe 3. The penalty delay period can be prevented by proper manipulation of the acknowledging valve Q as explained before.

It should be pointed out that the particular arrangement of circuits illustrated in Figs. 2 and 3 are not essential but have been shown and described as one possible arrangement of circuits for the control from the trackway of the apparatus illustrated in Figs. 1 and 1^a.

One object of my invention is the provision of means for insuring a maximum degree of safety in operation of trains with a minimum of interference with the normal operation of the train. With this purpose in mind I have so arranged the apparatus that the engineer, if alert, can always prevent the infliction of the penalty delay period, and by properly manipulating his brake application valve can completely prevent a brake application by the automatic application valve if the train is reduced to safe speeds. The apparatus automatically applies the brakes only in the event of carelessness or negligence on the part of the engineer or when the train speed is not maintained below a safe value.

Although I have herein shown and described only one form and arrangement of railway traffic controlling apparatus embodying my invention, it is understood that various changes and modifications may be made therein within the scope of the appended claims without departing from the spirit and scope of my invention.

Having thus described my invention, what I claim is:

1. In combination with an automatic fluid pressure braking mechanism for a railway train, manually operable means for applying the brakes, trackway apparatus responsive to traffic conditions in advance, train carried means for co-operating with said trackway apparatus and effective un-

der unsafe conditions in advance to apply the brakes automatically after a time interval the length of which is dependent upon the speed of the train, and means operating only when said manually operable means is shifted to brake applying position for delaying said automatic brake application for a fixed interval of time.

2. In combination with an automatic fluid pressure braking mechanism for a railway train, manually operable means for applying the brakes, trackway apparatus responsive to traffic conditions in advance, train carried means for co-operating with said trackway means and effective under unsafe conditions in advance to apply the brakes automatically after a time interval the length of which is dependent upon the speed of the vehicle, and means controlled by said manually operable means for modifying said time interval.

3. In combination with an automatic fluid pressure braking mechanism for a railway train, manually operable means for applying the brakes, a normally energized magnet, means effective after a time interval to apply the brakes automatically when said magnet is de-energized, and means for delaying said automatic application for a fixed interval of time when said manually operable means is operative to apply the brakes.

4. In combination with an automatic fluid pressure braking mechanism for a railway train, manually operable means for applying the brakes, a normally energized magnet valve, a repeater slide valve controlled by said magnet valve, a timing valve controlled in part by said slide valve and in part by means responsive to the speed of the train, means controlled by said timing valve for automatically applying the brakes and means for delaying said automatic brake application for a fixed interval of time when said manually operable means is operative to apply the brakes.

5. In combination with an automatic fluid pressure braking mechanism for a railway train, manually operable means for applying the brakes, a normally energized magnet valve, a blow-down valve responsive to the speed of the train, a timing valve controlled in part by said magnet valve and said blow-down valve for applying the brakes, and means controlled by said manually operable means for modifying the control of said timing valve by said blow-down valve.

6. In combination with an automatic fluid pressure braking mechanism for a railway train, a reservoir normally charged with fluid pressure, a blow-down valve comprising a port open to atmosphere and the size of which is varied in accordance with the speed of the train, means responsive to

traffic conditions in advance for connecting said reservoir with said valve, a timing valve responsive to the pressure in said reservoir for applying the brakes, and manually controlled means interposed between said blow-down valve and said reservoir.

7. In combination with an automatic fluid pressure braking mechanism for a railway train, manually operable means for applying the brakes, a reservoir normally charged with fluid pressure, a blow-down valve comprising a port open to atmosphere and the size of which is varied in accordance with the speed of the train, means responsive to traffic conditions in advance for connecting said reservoir with said valve, a timing valve responsive to the pressure in said reservoir for applying the brakes, and means operative when said manually operable means is shifted to the brake applying position for restricting the flow of fluid from said reservoir to said valve.

8. In combination with an automatic fluid pressure braking mechanism on a railway train, a reservoir normally supplied with fluid pressure, a blow-down valve comprising a port open to a region of lower pressure and the size of which is varied in accordance with the speed of the train, a manually controlled pilot valve comprising a large port and a restricted port, means for connecting said reservoir with said blow-down valve through one or the other of said ports in said pilot valve, and a timing valve responsive to pressure in said reservoir for applying the brakes.

9. In combination with an automatic fluid pressure braking mechanism on a railway train, a manually operable brake valve for applying the brakes, a reservoir normally supplied with fluid pressure, a blow-down valve responsive to the speed of the vehicle, means for connecting said reservoir with said blow-down valve, and means for normally interposing a large port between said blow-down valve and said reservoir but for interposing a restricted port between said blow-down valve and said reservoir when said brake valve is in the brake applying position.

10. In combination with an automatic fluid pressure braking mechanism on a railway train, a manually operable brake valve for applying the brakes, a normally energized magnet, means for applying the brakes after a time interval when said magnet is de-energized, such time interval being of maximum duration when the speed of the train is below a given value and of shorter duration when the speed of the train is above such value, and means controlled by said brake valve for modifying said interval.

11. In combination with an automatic fluid pressure braking mechanism on a rail-

- way train, a manually operable brake valve for applying the brakes, a normally energized magnet, means for applying the brakes after a time interval when said magnet is de-energized, such time interval being of maximum duration when the speed of the train is below a given value and of shorter duration, when the speed of the train is above such value, and means for 10 imposing said maximum time interval irrespective of train speed when said brake valve is operative to apply the brakes.
12. In combination with an automatic fluid pressure braking mechanism for a rail- 15 way train, a chamber normally supplied with fluid pressure, means responsive to the pressure in said chamber for applying the brakes, a magnet valve controlled by traffic conditions in advance, a repeater slide 20 valve controlled by said magnet valve, a speed governor responsive to the speed of said train, a blow-down valve controlled by said speed governor, a pin valve also controlled by said governor, a manually operable brake valve, a timing valve controlled by said blow-down valve, said repeater slide valve and said brake valve, and means controlled by said timing valve for connecting said chamber with said pin valve.
13. In combination with an automatic fluid pressure braking mechanism for a rail- 25 way train, manually operable means for applying the brakes, a chamber normally supplied with fluid pressure, means responsive to the pressure in said chamber for applying the brakes, a magnet valve controlled by traffic conditions in advance, a repeater slide 30 valve controlled by said valve, a speed governor responsive to the speed of said train, a blow-down valve controlled by said speed governor, a pin valve also controlled by said governor, a manually operable brake valve, a timing valve controlled by said blow-down valve, said repeater slide valve and said brake valve, and means controlled by said timing valve for connecting said chamber with said pin valve.
14. In combination with an automatic fluid pressure braking mechanism for a rail- 35 way train, a chamber normally supplied with fluid pressure, means responsive to the pressure in said chamber for applying the brakes, a manually operable brake valve, a pilot valve controlled by said brake valve; a repeater slide valve controlled by traffic conditions ahead of the train, a blow-down 40 valve and a pin valve controlled by the speed of the train; a timing valve controlled by said blow-down valve, said repeater slide valve and said pin valve.
15. In combination with an automatic fluid pressure braking mechanism for a railway train, a chamber normally supplied with fluid pressure, means responsive to the pressure in said chamber for applying the 45 brakes, a manually operable brake valve, a pilot valve controlled by said brake valve; a repeater slide valve controlled by traffic conditions ahead of the train, a blow-down valve and a pin valve controlled by the speed of the train; a timing valve controlled by said blow-down valve, said repeater slide valve and said pin valve.
16. In combination with an automatic fluid pressure braking mechanism on a railway train, a manually operable brake valve, a pilot valve controlled by said valve and having two passages of different sizes and automatic brake applying apparatus responsive to traffic conditions in advance and to the speed of the train and controlled by 50 said pilot valve.
17. In combination with an automatic fluid pressure braking mechanism on a railway train, a manually operable brake valve, automatic brake applying apparatus responsive to traffic conditions in advance and to the speed of the train, and a pilot valve controlled by said brake valve and effective only when said brake valve is in the 55 brake applying position for controlling said automatic apparatus.
18. In combination with an automatic fluid pressure braking mechanism on a railway train, means controlled by the speed of the train for automatically applying the 60 brakes, manually operable means for releasing the brakes after the expiration of a penalty delay period, and manually operable means effective prior to said automatic application for preventing said penalty delay.
19. In combination with an automatic fluid pressure braking mechanism on a railway train, means controlled by the speed of the train for automatically applying the 65 brakes, manually operable means for releasing the brakes after the expiration of a penalty delay period only if the speed of the train is below a predetermined value, and manually operable means effective prior to said automatic application for preventing 70 said penalty delay.
20. In combination with an automatic fluid pressure braking mechanism on a railway train, automatic means controlled by traffic conditions in advance and by the 75 speed of the train for applying the brakes, manually operable means for subsequently releasing the brakes after the penalty time interval, a manually operable acknowledging valve, and an automatic valve con- 80

- trolled by said acknowledging valve for preventing said penalty delay.
21. In combination with an automatic fluid pressure braking mechanism on a railway train, a magnet valve controlled by traffic conditions in advance, means controlled by said magnet valve and responsive to the speed of the train for applying the brakes, manually operable means for subsequently releasing the brakes after the expiration of a penalty delay period, and manually operable means effective subsequent to operation of said magnet and prior to the operation of said first mentioned means for preventing said penalty delay period.
22. In combination with an automatic fluid pressure braking mechanism on a railway train, a magnet valve controlled by traffic conditions in advance, a chamber normally supplied with fluid pressure, means responsive to the pressure in such chamber for applying the brakes, a reservoir normally connected with a region of lower pressure, means for at times supplying fluid pressure to said reservoir, and means controlled by said magnet valve for at other times connecting said chamber with said reservoir, and means for preventing the admission of fluid pressure into said chamber from said reservoir.
23. In combination with an automatic fluid pressure braking mechanism on a railway train, a magnet valve controlled by traffic conditions in advance, a chamber normally supplied with fluid pressure, means responsive to the pressure in such chamber for applying the brakes, a reservoir normally connected with a region of lower pressure, means for at times supplying fluid pressure to said reservoir, and means controlled by said magnet valve for at other times connecting said chamber with said reservoir, and a check valve interposed between said reservoir and said chamber.
24. In combination with an automatic fluid pressure brake application mechanism on a railway train, a chamber normally supplied with fluid pressure, means responsive to a reduction in the pressure in said chamber for applying the brakes, a reservoir normally connected with atmosphere, means responsive to the speed of the train for connecting said chamber with atmosphere, and means responsive to traffic conditions for connecting said reservoir with said chamber.
25. In combination with an automatic fluid pressure brake application mechanism on a railway train, a chamber normally supplied with fluid pressure, means responsive to a reduction in the pressure in said chamber for applying the brakes, a reservoir normally connected with atmosphere, a valve responsive to the speed of the train, and means responsive to traffic conditions in ad-
- vance for connecting said chamber with said reservoir and said valve.
26. In combination with an automatic fluid pressure brake application mechanism on a railway train, a chamber normally supplied with fluid pressure, means responsive to the pressure in said chamber for applying the brakes, a reservoir normally connected with a region of lower pressure, a magnet valve responsive to traffic conditions in advance, means controlled by said magnet valve and by the speed of said train and operative after a time interval following operation of said magnet valve to connect said chamber with a region of lower pressure and with said reservoir, a check valve interposed between said reservoir and said chamber, and manually operable means effective during said time interval for supplying said reservoir with fluid pressure.
27. In combination with an automatic fluid pressure brake application mechanism, a magnet valve, a repeater slide valve controlled by said magnet valve, means controlled by said slide valve for at times causing an automatic brake application, a reservoir normally not supplied with fluid pressure for subsequently controlling the release of the brakes, a manually operable valve, means controlled by said manually operable valve and by said slide valve for at times supplying said reservoir with fluid pressure.
28. In combination with an automatic fluid pressure braking mechanism, a valve for automatically applying the brakes when in its reverse position, a manually operable brake valve effective after a time interval following such automatic brake application to return said first valve to its normal position, and manually operable means for modifying said time interval.
29. In combination with an automatic fluid pressure brake application mechanism, a magnet valve, a repeater slide valve controlled by said magnet valve, an auxiliary slide valve controlled by said repeater slide valve, means controlled by said slide valves for at times causing an automatic brake application, a reservoir for controlling the subsequent release of the brakes, a manually operable valve, means controlled by said manually operable valve and by said slide valves for at times connecting said reservoir with a region of lower pressure and for at other times connecting said reservoir with a source of fluid pressure.
30. In combination with an automatic fluid pressure brake application mechanism, a magnet valve, a repeater slide valve controlled by said magnet valve, an auxiliary slide valve controlled by said repeater slide valve, means controlled by said slide valves for at times causing an automatic brake ap-

- plication, a reservoir for controlling the subsequent release of the brakes, a manually operable valve, means controlled by said manually operable valve and by said slide valves for at times connecting said reservoir with a region of lower pressure and at other times effective for a limited time interval to connect said reservoir with a source of fluid pressure.
- 10 31. In combination with an automatic fluid pressure brake application mechanism, a magnet valve, a repeater slide valve controlled by said magnet valve, an auxiliary slide valve controlled by said repeater slide valve, means controlled by said slide valve for at times causing an automatic brake ap-
- plication, a reservoir for controlling the subsequent release of the brakes, a second reservoir, normally supplied with fluid pressure, an acknowledging valve comprising 20 a valve chamber, means controlled by said manually operable valve for at times connecting said second reservoir with said valve chamber, and means responsive to the pressure in said valve chamber and controlled by said slide valves for at times connecting said first reservoir with a region of lower pressure and for at other times connecting said first reservoir with a source of fluid pressure. 25
